PRESSURE REGULATOR

Irving C. Jennings, South Norwalk, Conn.

Application May 29, 1935, Serial No. 24,139

3 Claims. (Cl. 200—83)

The object of this invention is to improve the operation of the electric switch, which is used in connection with the diaphragm of a vacuum or pressure regulator. In such an apparatus, the actuating fluid operates on the surface of a spring or weight pressed diaphragm which is connected to the switch, and the parts are arranged so that when certain pressures or vacuums are reached, the switch will be thrown to cut the operating means, usually an electrically driven pump, out of and into operation.

An electrical switch must open with a snap action to prevent arcing and for this purpose the switch is usually provided with a mechanically acting snap or tip over mechanism. In using such a vacuum pressure regulator, I have experienced a great deal of difficulty in getting a closely adjusted operation.

For instance, in using an ordinary vacuum pressure regulator to maintain a vacuum of between twenty-one and twenty-two inches, which is a desirable point for vacuum steam heating, I have found that the pump should be stopped and started at about one-half inch above and one-half inch below an average of twenty-one and one-half inches, or within a range of one inch of mercury. With the old arrangement, the finest range of adjustment possible was three inches of mercury and, therefore, it was necessary to have the pump start in operation at twenty-one inches and to cut out, to pull a vacuum up to twenty-four inches, which with hot returns often caused the pump to run all the time.

I discovered that this difficulty can be overcome by removing the mechanical snap action switch from an ordinary vacuum pressure regulator and by substituting therefor a single tilting mercury switch operated from the diaphragm and adjusted so that the drag of the mercury against the electrode or electrodes, as well as the friction of the mercury in its containing tube, will cause a delayed action, which will effect a small but actual difference in pressure between the on and off positions of the switch and which will cause the switch to open with a snap action. With this arrangement I can easily control the on and off positions of the switch within the range of an inch of mercury.

One embodiment of the invention is illustrated in the accompanying sheet of drawings, in which:

Fig. 1 is a sectional plan view of the improved apparatus.

Fig. 2 is a central sectional elevation, and

Figs. 3 and 4 are partial sectional elevations to illustrate the peculiar action.

Referring to the drawing and in detail, 10 designates a bottom plate, and 11 a cover plate, a diaphragm 12 being secured between 10 and 11, and these parts being held together by screws 13.

The actuating fluid is permitted to operate on the upper side of the diaphragm 12 through a coupling 110 on the upper or cover plate 11, 10 to which coupling a pipe can be connected.

Where the switch is to be used as a pressure regulator, the actuating fluid is admitted to act on the lower side of the diaphragm through a coupling 100, illustrated in dotted lines in Fig. 15 2, attached to the plate 10, the large vent opening in which is then closed.

Upper and lower plates 15 and 14 are placed on the sides of the diaphragm 12 and held there-to by a screw 16 threaded into a nut 17. A 20 supplemental diaphragm 18 is placed on top of the cover plate 11 and held in position thereon by a packing ring 19, a plate 22, and screws 21, threaded into the plate 22.

A supplemental contact 23 having a pin 24 25 bears on the supplemental diaphragm 18 and through the same on the large nut 17.

An inverted U-shaped bracket 25 is held on the base 22 by screws 26. An operating spring 27 is housed in the bracket 25, the lower end of 30 the spring being contained in a thrust block or cup 28 in which the pin 24 is fitted. A screw 29 extends down inside of the spring 27, the screw head being fitted in the top of the bracket 25 and having an integral collar 30 bearing against 35 said bracket. The spring 27 bears on a nut 32 threaded on the screw 29 so that by turning the screw the pressure of the spring can be adjusted.

A tilting plate 33 is pivoted by screws 34 to the sides of the bracket 25. The thrust block 28 40 is provided with arms 35 which are connected by screws 36 to tilting plate 33. One side of the tilting plate 33 is extended, as at 37, and is provided with a screw 38 having a check nut 39, the screw being set in position to engage the head of 45 a pin 40 sliding in a bracket 31 on plate 22, a spring 41 being arranged on the pin 40.

When the screw 38 is backed away so that it can never come in contact with the plate 40 throughout the travel of the extension arm 37, 50 the switch will open and close with a minimum difference in pressure.

By adjusting the screw 38 so that it comes in contact with the plate 40 through a portion of the travel of the extension arm 37, the switch 55

may be adjusted to open and close with a greater differential in pressure.

The tilting plate 33 is provided with an arm 42 carrying a clamp 43 held thereto by screw 44.

5 A mercury switch 45 is secured in said clamp 43. This mercury switch consists of a tube from which the air is exhausted and a globule of mercury M. One or more electrodes 46 and 47 is or are sealed into the tube of the mercury switch 10 10 45 and suitable lead in wires 48 and 49 are connected thereto.

The parts as thus far described can be adjusted to get a very delicate operation with the switch.

Assuming that the device is used as a vacuum 15 pressure regulator, under the figures previously described, when the switch is closed the same will be in the position shown in Fig. 2. As the vacuum on top of the diaphragm 12 is increased, the atmospheric air pressure on the under side 20 of said diaphragm will tilt the left hand end of the mercury switch 45 to its critical position, as shown in Fig. 3. In this position the globule of mercury M will tend to run or flow to the right, but will be held from so doing by the reluctance 25 of the mercury to move past the electrode or electrodes.

As the vacuum now slightly increases, the tendency of the mercury to flow by gravity to the right will overcome this resistance to flow, and 30 the mercury switch will move to its open position, as shown in Fig. 4.

Thus there will be a snap action of the parts between the position shown in Figs. 3 and 4, which is measured by the said retarding effect 35 of the mercury. This factor of resistance to flow can be made much less than the extra pressure necessary to obtain the throw of the switch to overcome any mechanical snap mechanism. Therefore, the mechanism described provides a 40 snap switch which can be very delicately adjusted.

I am aware that it is common to tilt a mercury switch by a fluid acting on a diaphragm, corrugated bellows or piston, but so far as I am 45 aware, the resistance to flow of a globule of mercury has never been employed as the sole means of providing for the necessary snap action.

The details and arrangements herein described may be greatly varied by a skilled mechanic without departing from the scope of my invention as expressed in the appended claims.

Having thus fully described my invention, what

I claim and desire to secure by Letters Patent is:—

1. A pressure regulator comprising a diaphragm on the surface of which an actuating fluid operates, adjusting means for determining the pressure at which said diaphragm operates, and a tilting mercury switch mounted for movement under the influence of said diaphragm, means to cushion movement of said switch, said mercury switch having an electrode positioned 10 at a substantial angle to and in the path of flow of the mercury and positioned to offer an obstruction to such flow of mercury whereby adherence of the mercury to the electrode will in itself cause a delayed action of the switch followed 15 by an actuation of the switch with a snap action.

2. A pressure regulator comprising a diaphragm on the surface of which an actuating fluid operates, adjusting means for determining the pressure at which said diaphragm operates, 20 a tilting plate connected to said diaphragm for direct actuation thereby, adjustable means to cushion downward movement of said tilting plate, and a tilting mercury switch mounted on said plate for movement therewith, said mercury 25 switch having an electrode positioned at a substantial angle to and in the path of flow of the mercury and positioned to offer an obstruction to such flow of mercury whereby adherence of the mercury to the electrode will in itself cause 30 a delayed action of the switch followed by an actuation of the switch with a snap action.

3. A pressure regulator comprising a diaphragm on the surface of which an actuating fluid operates, adjusting means for determining 35 the pressure at which said diaphragm operates, a tilting plate fulcrumed upon said diaphragm for direct actuation thereby, adjustable means located at one side of the fulcrum to cushion downward movement of said tilting plate, and a 40 tilting mercury switch mounted on said plate at the opposite side of said fulcrum for movement with the plate, said mercury switch having an electrode positioned at a substantial angle to and in the path of flow of the mercury and positioned 45 to offer an obstruction to such flow of mercury whereby adherence of the mercury to the electrode will in itself cause a delayed action of the switch followed by an actuation of the switch with a snap action.

IRVING C. JENNINGS.
